UNITED STATES PATENT OFFICE.

GEORGE H. PHELPS, OF WEST NEWTON, MASSACHUSETTS.

DESIGN FOR A STOCKING-SUPPORTER.

SPECIFICATION forming part of Design No. 19,515, dated December 17, 1889.

Application filed November 1, 1889. Serial No. 328,927. Term of patent 14 years.

To all whom it may concern:

Be it known that I, GEORGE H. PHELPS, a citizen of the United States, residing at West Newton, in the county of Middlesex and State of Massachusetts, have invented and produced a new and original Design for Stocking-Supporters, of which the following is a specification, reference being had to the accompanying drawings, forming part thereof.

Figure 1 of the drawings shows in perspective a stocking-supporter showing my design, and Fig. 2 a section in the line $x x$.

The leading feature of my design for a stocking-supporter consists in a raised edge or bead formed along the inner edge of the sides of the opening of the stocking-supporter from their point of convergence.

$a a$ represent the two converging sides, and b the back or cross-bar of the supporter.

The raised edges or beads $c c$ are arranged at the inner edges of the sides $a a$, and extend

from the point where the said sides converge upwardly for a distance nearly to the top of the sides, to present to the eye a good and well-rounded finished edge. ²⁵

I claim—

In the design for a stocking-supporter herein shown and described, the converging sides $a a$ of the supporter, connected at the top by the bar b , and the raised rounded edges or beads ³⁰ $c c$, arranged along the inner edges of the sides $a a$ and extending upwardly from their point of convergence toward the top of the sides, as set forth.

In testimony whereof I have signed my name to this specification in the presence of two subscribing witnesses.

GEORGE H. PHELPS.
